UNITED STATES PATENT OFFICE

MAX JUNG, OF DARMSTADT, GERMANY

METHOD OF AND APPARATUS FOR REMOVING MOISTURE FROM SOLID MATERIALS

Application filed July 11, 1928, Serial No. 291,906, and in Germany June 17, 1927.

My invention relates to a method of, and apparatus for, removing moisture from solid materials, and it is an object of my invention to provide a method and apparatus of the kind described in which dynamic and pneumatic action are combined.

My invention may be applied to the drying of mineral and vegetable materials.

In an apparatus for performing my method I may provide a centrifugal apparatus in combination with a fan which may be positively connected with the centrifugal apparatus so as to rotate at the same speed, or adapted to rotate at a speed other than that of the apparatus. In the latter case, it is also possible to rotate the centrifugal apparatus and the fan in opposite directions, and it will be understood that any combination of speeds of rotation and air velocity may be obtained in this manner.

It is also possible to combine the centrifugal apparatus and the fan into a single unit by designing the chambers of the centrifugal apparatus as fan chambers, suitable vanes being provided.

In cases where it is particularly difficult to separate the moisture from the material or in the case of a very thick liquid, the pneumatic action may be exerted by vacuum and pressure in combination so as to increase the separating action. In an apparatus of the latter type, the impeller may be provided with a hollow shaft for supplying a gas thereto, or for connecting it with a vacuum or the apparatus is equipped with a casing under pressure or under vacuum.

When compressed gas is employed, the inlet side of the apparatus is so designed that the gas is forced through the chambers or filters of the impeller. When vacuum is employed, corresponding equipment is provided at the outlet, or outlets, for the water and the gas, if any, separated from the material. As mentioned, any combination of compressed gas and vacuum may be provided.

I may also provide means for exerting vibration on the apparatus with a view to accelerate or to assist the separation. Any part of the apparatus, for instance, its im-

peller, or the complete apparatus, may be subjected to vibration.

My invention also relates to suitable designs of filters. Any type of filters, as slotted screens, fabrics, osmotic filters, and the like may be provided. In the case of slotted screens, the slots are preferably extended in the direction in which the material is flowing so as to prevent clogging.

Preferably, the filters are equipped with frames to facilitate their insertion and exchange, so that the same apparatus may be operated with various kinds of filters. Osmotic and similar filters are preferably not only exchangeable but also adapted to be turned over so as to be used repeatedly and to be cleaned automatically.

If desired the material which has been treated in the centrifugal apparatus, may be projected into flowing gas in order to further reduce its moisture content, or to prevent deposition of condensate from moist air discharged with the material, conglomeration of the material and reabsorption of moisture.

Means as heating jackets or the like may be provided in connection with the apparatus, and the apparatus may also be combined with further drying means.

The chambers in which the material and the mixture of liquid and gas which has been separated from the material, are flowing, are separated by an air cushion. The air required for the cushion is admitted through openings in the casing of the apparatus and is admitted to either chamber through an adjustable annular slot.

My method and apparatus may also be used for the separation of dust from gases, for separating gases and gas mixtures, and for removing moisture from gases.

In the drawings affixed to this specification and forming part thereof, apparatus in which my method may be performed, are illustrated diagrammatically by way of example.

In the drawings

Fig. 1 is an elevation of a centrifugal apparatus in which the impeller and the fan are combined into a single unit.

Fig. 2 is a section on the line II-II in Fig. 1.

Fig. 3 is a diagrammatic illustration, on a larger scale, of a combined fan and impeller,

Fig. 4 is an axial section of an apparatus in which gas under pressure and suction may be applied.

Referring now to the drawings, and first to Figs. 1 and 2, A is a hopper for supplying material to the apparatus, B is the casing of the apparatus having an outlet C for the air or gas which have been moved through the apparatus or through the material to be treated, or are contained in the material, an outlet D for the separated water, and an outlet E for the treated material, F is the shaft 10 of the fan and impeller unit in the casing B, d is a boss on the shaft F, b is the impeller or centrifugal part of the apparatus, c is its fan part, and a is a partition between the two parts. As mentioned, the parts may be separated and each provided with driving mechanism of its own, so that each part may operate at different speed, and the parts may rotate in opposite directions.

Referring now to Fig. 3, this shows diagrammatically a chamber of the apparatus, with a fan of its own. The material to be treated flows in a thin layer and in a steady stream from the axis of the impeller toward its perimeter along the partition or filter e, as indicated by the radial arrow. In this manner a layer or jet is ejected continuously at the perimeter of the impeller. As indicated by the arrows crossing the radial arrow, the air permeates the comparatively thin layer substantially at right angles to the direction in which the material flows. Vanes g are arranged in front of the filter r. The impeller rotates in the direction of the arrow, and f are vanes at the rear of the filter. The vanes 30 g serve for suitably guiding the material and the air, as indicated by the arrows. The air after flowing through the filter e is separated into a plurality of layers by the vanes f in order to avoid whirling.

Referring now to Fig. 4, i is a vertical hollow shaft to which compressed gas is supplied through a pipe G and a stuffing box H. Suitable radial passages connect the chambers h of the impeller a with the hollow shaft 50 i and gas chambers, not shown, may be provided in connection with the chambers h in order to facilitate the distribution of the gas. Nozzles, not shown, may be provided for supplying the gas to the several chambers.

If it is desired to operate the apparatus under a vacuum, suction instead of pressure is applied to the pipe G and the flow is now reversed.

If it is desired that the impeller a should rotate in gas under pressure, a gas chamber k is formed above the impeller by a suitable casing, and gas under pressure is supplied to the chamber, or chambers, k through a pipe I. If, on the other hand, it is desired that the impeller should rotate in a vacuum it is

equipped with a suitable barrel m and a stationary plate l is provided in close vicinity to the lower edge of the barrel m, a suction pipe K being provided for evacuating the impeller.

Means may be provided for projecting the material into flowing air, as mentioned above. If this is desired, the impeller is provided with a cowl n in which an air cushion n' is rotating, the air in the cushion being renewed by discharge openings r in the barrel m of the impeller. The air and the material are discharged across the edge v of the cowl n. The water and the air from the impeller are discharged through a common outlet p in which an inclined plate s is provided for the separation of the material and the mixture of air and water. The upper end of the plate or conical partition s is packed at the barrel m of the impeller by an annular cavity into which air is continuously forced through the rotation of the impeller, which air is then discharged into the chamber p and into a chamber q below the partition s as follows: t is an annular section having a flute u which, with the exception of a small air discharge gap, is covered by rings v and w so that annular cavities are formed between the rings w, v, and the barrel m. The barrel m and the section t are perforated at x so that the flute u is connected with the inside of the barrel. When the barrel rotates, air is forced into the flute u through the holes x, and is discharged into the chambers p and q through narrow gaps past the rings v and w. The gaps may be regulated by making the rings v and w adjustable. In this manner a very simple, practically frictionless, permanent and very effective packing is obtained for separating the chambers p and q.

Various changes may be made in the details disclosed in the foregoing specification without departing from the invention or sacrificing the advantages thereof.

I claim:—

1. A centrifugal apparatus for removing moisture from continuously flowing solid material, comprising means for subdividing the material into thin layers, and vanes for directing a drying agent through said material transversely to the direction in which said material flows.

2. A centrifugal apparatus for removing moisture from continuously flowing solid material, comprising means for subdividing the material into thin layers, and vanes for directing a gaseous drying agent through said material transversely to the direction in which said material flows.

3. A centrifugal apparatus for removing moisture from continuously flowing solid material comprising an impeller with a substantially radial foraminated partition, means at the centre of said impeller for ad-

mitting the material to be treated to one side of said partition, means for discharging the material at the perimeter of said impeller, and vanes for directing a drying agent trans-

5 versely through said partition.

4. A centrifugal apparatus for removing moisture from continuously flowing solid material, comprising a rotary impeller, means on said impeller for subdividing the 10 material into thin layers comprising a filter extending in the radial direction of said impeller, and vanes for directing a drying agent through said material transversely to said radial direction.

15 5. A centrifugal apparatus for removing moisture from continuously flowing solid material, comprising a rotary impeller, means on said impeller for subdividing the material into thin layers comprising a filter 20 extending in the radial direction of said impeller, a set of vanes for supplying air to said filter and arranged at one side of and angularly related to said filter, and a second set of vanes for receiving and subdividing 25 the issuing mixture of agent and liquid and arranged at the opposite side of and angularly related to said filter.

In testimony whereof I affix my signature.
MAX JUNG.
